PULSE SYNTHESIZING SYSTEM

Donald D. Grieg, Forest Hills, N. Y., assignor to
 Federal Telephone and Radio Corporation,
 New York, N. Y., a corporation of Delaware

Application December 19, 1945, Serial No. 636,023

5 Claims. (Cl. 178—44)

1

This invention relates to a method and apparatus for synthesizing similar recurring undulations on an electromagnetic wave. More particularly, it deals with a system for dividing the undulations into segments to produce a train of pulses, utilizing or transmitting the train of pulses, and then recombining the pulses of the train to reproduce the original undulations.

It is an object of this invention to recombine a train of pulses comprising segments of undulations to reproduce said undulations in a novel and effective manner.

Another object of this invention is to divide, and then reproduce undulations in a novel and effective manner.

Another object is to divide, transmit, and reproduce similar recurring undulations with substantial simulation of shape of the original undulations.

Another object is to provide means for carrying out the above objects.

Still other objects and features of this invention will appear from time to time in the description which follows:

Generally speaking, this invention comprises a method for dividing periodic recurring undulations into segments to produce a train of pulses having widths corresponding to the widths of the undulations at corresponding segmenting levels; transmitting and receiving or otherwise utilizing the train of pulses without distorting the time location of the edges thereof; and then combining the pulses of the train to reproduce the original undulations. The more numerous the segments in which the original undulation is divided, the more accurate is the reproduction of the original undulation. The undulations which are segmented should be recurrent, although their frequencies need not be constant.

Segmentation or division of the undulations may be accomplished by double clipping segments at different amplitudes from a plurality of recurring undulations to produce the above-mentioned train of segment pulses.

The reproduction of the original undulations from the train of pulses may comprise a de-blocking circuit for separating the pulses corresponding to the same clipping level into separate pulse trains. These pulse trains are then delayed and combined so that the different segments may be superimposed to reproduce the originally segmented undulation.

In order to select the proper segment pulses in the pulse trains, marker pulses may be placed at regular intervals along the original pulse train.

2

These marker pulses may be produced from the original undulations before they are segmented and may be eliminated in the de-blocking circuit. The marker pulses may comprise pulses of very

5 short duration which either have a greater amplitude than the segment pulses of the original pulse train, or comprise a pair of pulses closely spaced together which have the same amplitude as the segment pulses on the original pulse train.

10 If desired, an indicating device may be employed both in the circuit which divides the pulses and in the circuit for recombining the pulses. This indicating device may comprise a cathode ray tube with viewing screen upon which the pulses may be superimposed to produce a pattern related to the shape of the original undulation. The sweep circuits for such an indicating device may be controlled by the marker pulses produced from the original undulations.

15 These and other objects and features of this invention will become more apparent upon consideration of the following detailed description of the embodiments to be read in connection with the accompanying drawings in which:

20 Fig. 1 is a schematic wiring diagram partially in block for producing the original pulse train of this invention;

25 Fig. 2 is a schematic wiring diagram of another embodiment of the marker pulse circuit shown in Fig. 1;

30 Fig. 3 is a graph of wave forms useful in explaining the operation of the systems of Figs. 1 and 2;

35 Fig. 4 is a schematic block wiring diagram for synthesizing recurring undulations from a train of pulses; and

Fig. 5 is a graph of wave forms useful in explaining the operation of the system of Fig. 4.

Referring to Figs. 1 and 3 a wave containing 40 similar recurring undulations, such as wave 1 shown in Fig. 3, is introduced into the system of Fig. 1 through line 2 and is passed to a variable delay device 3 and a shaper 4. Variable delay device 3 may comprise any suitable circuit

45 for delaying the wave 1 without distorting the shape of undulations, such as a network of inductances and condensers to simulate a transmission line. From the delay device 3 is withdrawn the delayed wave 5 which is passed through line 6 to the amplitude double clipper 7.

The shaper 4 may comprise circuits for producing the pulse wave 8 from the undulations of the wave 1, such as clippers, differentiators, amplifiers, etc. Pulse wave 8 is withdrawn from

shaper 4 through line 9, passed to the scanning circuit and to marker pulse circuit 11.

The scanning circuit 10 comprises a variable scanning frequency divider 12 which may comprise a multivibrator, to produce the wave 13 which is then passed through line 14 to the saw-tooth wave generator 15. From generator 15 is withdrawn the saw-tooth wave 16 through line 17 which is passed to amplitude double clipper 7.

The amplitude double clipper 7 may comprise a double diode 18 and suitable coupling circuit as shown. The delayed pulse train 8 and the saw-tooth wave 16 are both applied to the plate 19 of the tube 18. Successive pulses of the train 5 are clipped at gradually increasing amplitudes, as shown along the line 20 in Fig. 3, due to the increasing voltage along the sloping edge of the wave 16. The width of the clipping segment 21 is determined by the adjustment of the resistance 22 in the cathode circuit of the tube 18. From the plate 23 of the tube 18 is withdrawn the train of pulses 24, corresponding to the shaded segments above the line 20 and corresponding in width to the width of the corresponding undulations of the wave 5 at the corresponding clipping levels. The pulses on the pulse train 24 are withdrawn from the amplitude double clipper circuit 7 through line 25 and thence into a mixer 26.

For producing a double marker pulse, the marker pulse circuit 11 may comprise a variable frequency divider 27 and/or a decoupler delay line 28 and 29. If desired, however, the pulses from shaper 4 may be passed directly to the mixer 26 through line 30 having switch 31 and line 32. In the specific wave form shown, there are two different types of alternately recurring undulations on the wave 1 which may be considered together, therefore the pulse wave 8 is passed through the frequency divider 27 from which is removed the pulse wave 33 which is then passed through line 34 to join with line 32 coupled to the mixer 26. Pulse wave 33 when mixed in mixer 26 with the pulse train 24, produces wave 34 which is then withdrawn through line 35 to a transmitter or similar utilization circuit.

Instead of producing a single marker pulse 36 shown on wave 34, which marker pulse has an amplitude greater than that of the segment pulses from wave 24 thereon, a different type of marker pulse may be produced, such as a double marker pulse by passing the pulse wave 33 through switch 37 into the decoupler and delay line circuits 28 and 29. The decoupler 28 may comprise a suitable tube 38 which prevents any reflections from the reflecting delay line 29 from feeding back into the other circuits of the system. The delay line comprises a network of inductances and condensers 39 and 40, respectively, with a balanced resistance 41 across the one end. The other end of the delay line is open to prevent inversion of the reflected wave. By combining the original pulse wave 33 with the reflected pulse wave from the network 29 there is produced a double marker pulse wave 43 which is withdrawn through line 44 and passed through line 32 to the mixer 26. The mixing of the double marker pulse wave 43 with the wave 24 produces the pulse wave 45 having double marker pulses 46 between each pair of segment pulses. Both the segment pulses and the marker pulses in the wave 45 may be of the same amplitude.

Instead of the scan circuit 10 producing the saw-tooth wave 26 each undulation or adjacent pairs of undulations on the wave 5 may be clipped

along a step wave, such as wave 47, produced in the scan counter circuit 48 shown in Fig. 2. This circuit 48 may comprise a scan frequency divider 12a, similar to divider 12, a pair of unidirectional valves or diodes 49 and 50, a condenser 51, a very large condenser 52, a very large resistance 53, and a gas filled triode 54 biased through a battery 55. In this embodiment the scanning frequency divider 12a is adjusted to produce a wave similar to 33 shown in Fig. 3. Each positive pulse on the wave 33 puts a charge on the condenser 51 which charge is passed through the valve 50 and is applied to the larger condenser 52. The charge on the condenser 52 is gradually built-up in steps by each additional pulse in the pulse wave 33 until a voltage is reached which causes the gas filled tube to discharge the condenser 52. The steps of the wave 47 gradually diminish in amplitude as the charge on the condenser 52 is increased. The diode 49 in the plate circuit potential of the tube 50, prevents any negative pulses or other variations in the pulse wave 33 from effecting the charge build-up on the large condenser 52. The resistance 53 between the condenser 52 and the gas filled tube 54 must be very large to prevent leakage of the condenser 32. The gas filled tube 54 is biased through a battery 55 so that when the voltage on the condenser 52 reaches the amplitude 59 shown on wave 47, the tube becomes conductive and discharges the condenser 52 along the line 60 of the step shaped pulse on the wave 47. When the condenser 52 is completely discharged the tube 54 again becomes non-conductive and the next successive pulse of the wave 33 starts building up charges to produce a new step shaped pulse on the wave 47. The wave 47 is withdrawn from the circuit 48 through the guard condenser 61 and then passed through line 16 entering the amplitude double clipper 7 shown in Fig. 1. The step shaped pulse wave 47 is shown to clip successive pulses of the wave 5 above the step line 62 in Fig. 3. The shaded segments which are clipped from these pulses produce a segment pulse train similar to train 24. One advantage of the circuit 48 over that of circuit 15 is that the segments from the pulses are taken parallel to the base of each pulse. However, if the angle of the sloping edge of the saw-tooth wave 16 is sufficiently small, very little, if any, distortion will be caused by the sloping segments produced therefrom. This is also true if the pulse which is being clipped by the wave 16 is of short duration.

If desired, the pulse produced by the system described above in Fig. 1 may be indicated on a suitable cathode ray indicating device, the sweep circuit of which may be operated by the pulse wave 33 coupled to the frequency divider 27 through line 63. The pulses produced in the circuit in line 25 are applied to the vertical deflection plates 64 of the cathode ray device 65 through line 66. The sweep circuit 67 coupled to line 63 may comprise a saw-tooth wave generator, similar to that of 15, which may comprise a triode 68 the grid of which is suitably biased to cut-off through the resistor 69, and a condenser 70 coupled across the triode 68 which is charged through resistance 71 by the plate voltage supply. When the leading edge of a positive pulse of the wave 33 is passed through line 63 on to the grid of the tube 68, the tube 68 is caused to conduct current and the condenser 70 is discharged. But since the pulses on the wave 33 are of short duration the tube 68 is immediately cut-off by the trailing edge of the positive pulse. The con-

denser 70 is again permitted to charge gradually from the plate voltage supply through resistance 71 to produce the sloping edge of the saw-tooth of the wave 72. This wave 72 is withdrawn from the circuit 67 through the line 73 and applied across the horizontal deflecting plates 74 of the tube 65. The value of condenser 70 is adjusted so that the slope of the teeth on wave 72 will be substantially a straight line in order to effect an even sweep across the plates 74 of the device 65. The pulses of the original pulse train 24 produce the pattern 75 shown on the screen of the device 65 in Fig. 1. Since different sloping edge of the undulations on the wave 1 produce various spacing between the vertical lines of the patterns 75, a definite correlation may be made between the shape of the pattern and the shape of the undulations. For example, the straight edge 76 of the pulse 77 on wave 1 produces a heavy line 78 in the pattern 75 while the sloping edge 79 of the same pulse produces evenly spaced vertical lines 80 in the pattern 75. Similarly, the curved edges of the recurring undulations 81 on the wave 1 form differently spaced vertical lines in the second portion 82 of the pattern 75 shown on the screen of the device 65.

After utilization or transmission, the wave 35 or 45 produced in the circuit shown in Fig. 1 or any similar pulse wave may be synthesized by the circuit shown in Fig. 4. For convenience the waves 34 and 45 are reproduced again as waves 83 and 84, respectively in Fig. 5. The different amplitude sections clipped from the original wave are lettered as sections *a*, *b*, *c*, *d* above corresponding portions of the waves 83 and 84.

If the wave 84 is received over line 85 in Fig. 4, it is passed through line 86 into the mixer shaper circuit 87 which may comprise a decoupler and delay line 88, similar to 28 and 29 shown in Fig. 1, from which is withdrawn the complex wave 89. Two of the double marker pulses have thus been superimposed upon each other to produce the larger amplitude pulses 90. However, since a number of segment pulses on the wave 84 are also superimposed to produce step shaped pulses of equal amplitudes, such as pulses 91, it is necessary to select and segregate the pulses 90 from the wave 89, by differentiating the wave 89 in the differentiator 92 from which is removed pulse wave 93. Pulse wave 93 is then clipped in clipper 94 along level 95 to produce a pulse wave only of the pulses 90. This pulse wave is then passed through line 96 to the deblocking circuit 97 for separating the different sections *a*, *b*, *c*, and *d* from the received wave 84.

If the wave 83 is received, it is not necessary to pass it through the circuits 88 and 92, but only through the clipper 94 which may be done by closing the switch 98 and opening the switch in line 86 from the line 85. Marker pulses 99 are then clipped from the wave 83 along the clipping level 100 to produce a wave only of pulses 99, similar to the wave of pulses 90.

The deblocking circuit 97 may comprise a short variable delay device 101, a multivibrator circuit 102, a series of delay devices 103, 104, 105, and a series of mixerclippers 106, 107, 108 and 109. The short delay device 101 delays the wave of pulses 90 or 99, so that it is out-of-phase with the marker pulses on the waves 83 and 84. Then delayed 70 pulses 90 or 99 are caused to trigger the multivibrator circuit 102 to produce the deblocking wave 110. Wave 110 is aligned to deblock the section *a* from either wave 83 or 84. The other sections *b*, *c* and *d* of the received wave 83 or 84

may be deblocked by passing the wave 110 through the delay device 103, 104 and 105 to produce deblocking wave 111, 112, 113, respectively.

Deblocking waves 110, 111, 112, 113, are then 5 mixed in the mixer clippers 106, 107, 108, and 109, respectively with the original wave 83 or 84 from line 85 through line 114. On these mixer clippers are produced waves 115, 116, 117, 118 corresponding to segments *a*, *b*, *c*, and *d*, which 10 waves are clipped along the line 119, 120, 121, 122 to produce a series of pulse trains corresponding to segment pulses of sections *a*, *b*, *c*, and *d*, respectively.

Segments *a*, *b*, *c*, and *d* may be combined or 15 superimposed to reproduce the original undulations from which they were divided by delaying the clipped pulse trains, corresponding to segments *a*, *b*, and *c* in delay devices 123, 124, 125 so that the pulses of each train are synchronized 20 and in phase with each other and with pulse segments *d* withdrawn from mixer clipper 109 through line 126. The resulting synchronized pulse trains 127, 128, 129 and 130 are derived for 25 sections *a*, *b*, *c* and *d* respectively. All of these trains are now introduced into the mixer 131 which may comprise a parallel network of triodes to prevent the impulses from one delay device from feeding back into the circuit of another. The aligned pairs of pulses are thus superimposed 30 to reproduce undulations similar to undulations 77 and 81 of the original pulse wave 1, shown on wave 132 which may be withdrawn to suitable utilization circuits through line 133. The utilization circuits coupled to line 133 may comprise 35 modulation circuits, control circuits, and other circuits wherein the slope and shape of the true leading and trailing edges of undulations are important in their operation. The system of this invention is particularly useful in breaking down a pulse of a definite shape so that it may be transmitted and operated upon by circuits which would distort its shape, and then recombining the pulses so operated on to reproduce the original undulation having a given shape.

45 Although the frequency of the undulations on wave 132 is not as great as that in the original pulse wave 1, the true shape of the undulations 77 and 81 are reproduced. The four different amplitude sections were merely chosen here to 50 illustrate this invention, however, in accurate reproductions 10 or more different amplitude sections should be taken.

An indicator circuit 134 also may be coupled to lines 85 and 96 through lines 135 and 136 respectively to indicate the type of pulses received. The circuits 134, may comprise a scanning frequency divider 137 and saw-tooth wave generator 138, similar to the scanning circuit 10 shown in Fig. 1, and the sweep generator 139 60 for a cathode ray device such as 140, may be similar to circuit 67 shown in Fig. 1. The original received wave 83 or 84 may be mixed in mixer 141 with the saw-tooth wave 142 from the saw-tooth wave generator 138 to produce the wave 144 which is applied across the deflection plates 147 of the device 140. The sweep circuit 139 coupled to the output of clipper 94 through line 136 comprises a saw-tooth wave generator which produces the wave 146 which is applied 65 across the deflection plates 145 of the device 140. The resulting pattern 148, produced on the screen of the cathode ray device 140 in Fig. 4 shows the separate segment pulses of the received train superimposed one upon the other.

An indicating device, such as a cathode ray

oscillograph, may be connected directly to line 133 if desired so that the exact undulation synthesized in the circuit of Fig. 4 may be observed.

Although the above invention refers to means for utilizing a given undulation in circuits which ordinarily would distort the amplitude and slopes of the edges of the undulations, the system disclosed in Fig. 4 may be employed for recombining any series of pulses of different widths to produce an undulation, that is, for synthesizing 10 pulses of one type from a series of pulses of another type.

While the above is a description of the principles of this invention in connection with specific apparatus and particular modifications 15 thereof, it is to be clearly understood that this description is made only by way of example and not as a limitation on the scope of this invention as defined in the objects and accompanying claims.

I claim:

1. A method of transmitting periodic recurring undulations of an electromagnetic wave comprising: clipping horizontal segments from a plurality of similar successively occurring undulations at different amplitudes to produce a train of pulses of the same amplitude, the widths of which correspond to widths of the undulations at corresponding clipping levels, transmitting and receiving said train of pulses, and vertically combining successive pulses of the received train to reproduce said undulations. 25

2. A method of utilizing periodic recurring undulations of an electromagnetic wave comprising: dividing said undulations into segments at different amplitudes to produce a train of pulses, producing a train of marker pulses from said undulations which are out of phase with the train of pulses, combining the marker pulses and pulses on a single pulse wave, and then vertically combining the pulses on the single pulse wave controlled by said marker pulses to reproduce 30 said undulations.

3. In a system for producing a single recurring undulation on an electromagnetic wave from a 45 train of pulses of a repetitive series of pulses of given widths interleaved with marker pulses, comprising: means for separating said marker

pulses on said train, means for producing a separating wave from said separated marker pulses, means for producing a plurality of separated waves out of phase with each other and in phase with each of the pulses of each series on said train of pulses, means for combining said separating and delayed separated waves with the original train of pulses to produce a plurality of pulse trains corresponding to each pulse in said series, means for phasing the pulses on the resulting pulse trains, and means for vertically combining the phased pulse trains to produce said single recurring undulation.

4. The system of utilizing periodic recurring undulations of an electromagnetic wave comprising: means for dividing said undulations into segments at different amplitudes to produce a train of pulses, and means for vertically combining the pulses on said train to reproduce said undulations.

5. A system for transmitting periodic recurring undulations of an electromagnetic wave comprising: means for clipping horizontal segments from a plurality of similar successively recurring undulations at different amplitudes to produce a train of pulses of the same amplitude, the widths of which correspond to the widths of the undulations at corresponding clipping levels, means for transmitting and receiving said train of pulses, and means for separating and vertically combining the pulses on said train to reproduce said undulations.
